UNITED STATES PATENT OFFICE.

HERMANN F. CUNTZ, OF HARTFORD, CONNECTICUT, ASSIGNOR TO THE
POPE MANUFACTURING COMPANY, OF SAME PLACE.

DESIGN FOR A CRANK-SHAFT BRACKET.

SPECIFICATION forming part of Design No. 26,979, dated April 27, 1897.

Application filed March 11, 1897. Serial No. 627,063. Term of patent 14 years.

To all whom it may concern:

Be it known that I, HERMANN F. CUNTZ, a citizen of the United States, and a resident of Hartford, in the county of Hartford and State of Connecticut, have invented a new and useful Design for Crank-Shaft Brackets for Bicycles; and I do hereby declare the following, when taken in connection with the accompanying drawings and letters of reference marked thereon, to be a full, clear, and exact description of the same, and which said drawings constitute part of this specification, and represent, in—

Figure 1, a top view of the device; in Fig. 2, 5 a side view of the device; in Fig. 3, a side view of the device looking from the left, and in Fig. 4 a perspective view.

My invention relates to a design for a bracket or hanger adapted for use in connection with or as a part of the frame of a bicycle or tricycle, in which it is located at a somewhat central and lower part of the frame; and said invention consists in the configuration of the structure, as hereinafter described 5 and as shown in the accompanying drawings.

The bracket comprises a main cylindrical portion or barrel *a*, from the side of which, near the larger end, extends a cylindrical part *b*, these two parts being located at substantially right angles to each other.

On the end of the barrel adjacent to the projection *b* is an enlargement *c* with the walls of the main part *a* widening out at the inner end to form the enlargement, the periphery of which is narrow as compared with the total 35 width of the bracket.

The end of the enlarged part *c* presents a substantially flat surface transversely of the axis of the barrel, and the bracket as viewed from the opposite side shows the circular 40 end, a cylindrical projection on one side, and the circular bounding-lines of the enlargement beyond.

The essential feature of my improved design or bracket is the cylindrical body part 45 terminating in the end enlargement and having the lateral cylindrical projection, as shown.

I claim—

The design for a crank-shaft bracket for a 50 bicycle-frame, substantially as shown.

In testimony whereof I have signed this specification in the presence of two subscribing witnesses.

HERMANN F. CUNTZ.
